UNITED STATES PATENT OFFICE.

EMANUELE RUFFO AND VITO CALDERARO, OF ROME, ITALY.

FIRE BAR.

Application filed July 7, 1922. Serial No. 573,388.

To all whom it may concern:

Be it known that we, EMANUELE RUFFO and Vito CALDERARO, both subjects of the King of Italy, and both residing at 300 5 Corso Umberto, Rome, in the Kingdom of Italy, have invented certain new and useful Improvements in Fire Bars, of which the following is a specification, reference being had therein to the accompanying drawing.

10 The invention relates to grate or fire bars for use with solid fuel.

The fire bar according to the invention consists of two members which are arranged in an inclined position and contact at their 15 lower edges so as to form an acute angle between them with the aperture towards the grate area. The two bar members are made of strips of sheet iron or section iron and they are provided on their inside faces with 20 projections, ridges or the like which extend lengthwise of the members approximately along the center line thereof, the projections of two cooperating bar members being so shaped and arranged that they engage each 25 other and form the bottom of an open channel which extends lengthwise of the bar and is intended to contain ashes or like combustion products. The bar members are seated in transverse frames which hold them in 30 their respective inclined position and by interposing lifting pieces between the bottom wall of the seat and the lower contacting edges of the bar members it is possible to alter the angle formed by the two members 35 and to increase the aperture on the grate area and diminish in this way the air space between the bars.

In order that the invention may be readily understood the same will be described with 40 reference to the annexed drawing wherein Figures 1 and 2 show sectional views of two different constructional forms of the bars with the holding frames; Figure 3 is a plan view thereof; and Figure 4 is a sectional 45 view of a form of the invention as shown in Figure 2 with the lifting piece beneath the lower edges of the bar members.

As shown in the drawings, the fire bar consists of two members 1 and 2 which in the 50 example shown in Figure 1 are of sheet iron with a projection formed therein in the shape of a ridge 3 and in the construction illustrated in Figure 2 are of section iron with a web-like projection 4. These projec-

tions extend lengthwise of the bar members 55 approximately at the center line thereof. The cooperating bar members are arranged in an inclined position so as to contact at their lower edges and to form between them an acute angle with the aperture towards 60 the grate area. The projections on the two associated bar members are facing each other and engage one another so that two channels will be formed lengthwise of the bar, an upper channel 5 of substantially trapezoidal 65 shape and opening towards the grate area and a lower channel 6 of substantially triangular shape between the projections and the contacting edges of the bar members. The fire bars are held in seats 7 in frames 10 70 which are arranged transversely below the ends of the bars, the seats 7 being shaped in such a way that there are only two contacting points 8, 9 between the frame and one end of each bar member in order to avoid undesirable frictional contacts and deformations of the bars. The contacting edges of 75 the bar members rest on the bottom wall of the seat 7 and it is evident that when strips or lifts 15 of suitable thickness are interposed between the bottom wall and the contacting edges of the bar members the angle between these members will be increased 80 and their aperture on the grate area be increased and the air spaces 11 between the 85 neighbouring bars be diminished.

During operation, the upper channels 5 of the bars, which open onto the grate surface, will fill up with ashes or like combustion products and the fuel will thus be supported almost exclusively by the refractory mass of ashes or the like and contact between the fire and the metallic area will be reduced to a minimum. In this way, adhesion of slag or cinder to the fire bars and a choking 90 up of the bars is efficaciously avoided and this not only facilitates the cleaning of the grates, but is also conducive to a great economy of fuel and to a more uniform and regular combustion process and aids for a 95 longer life of the fire bars which are protected against excessive heat also by the air circulation inside the lower channels 6 and along their outside surfaces. Deformations of the bars are avoided by the longitudinal 100 projections which assure the required rigidity of the bar members and prevent bending stresses making themselves felt in ver-

tical or horizontal directions. The invention also avoids all danger of the bar members falling into the ash-pit, as they are securely held within the seats in the transverse frames. Each bar member may be separately removed and replaced when necessary and the longitudinal projections are so arranged that the bar member may be inverted and the lower edge be turned upward when 10 the upper edge has become unserviceable.

A further advantage of the fire bars according to the invention is that they allow the width of the bars and thus of the air spaces being altered in accordance with requirements. This is obtained by the lifts 15 as set forth which are interposed between the contacting edges of the bar members and the bottom of the seats so as to increase the divergence of the members, whereby the 20 opening of the bar on the grate area is increased and the width of the air space diminished.

The bar members are easily constructed of one single strip of sheet iron or of section 25 iron having a thickness of from 1 to 3 millimeters according to the length required for the grate and the ridges in the sheet iron may be readily produced by a rolling mill or the like. The bars are very light on account of the channels provided therein, and 30 the bar members are easily transported and stored, as they may be placed one above the other in heaps, which feature is particularly important when used on ships.

What we claim is:

1. In a grate, a grate bar for use with solid fuel, comprising two bar members arranged in an inclined position with their lower edges in contact, longitudinal projections on the bar members approximately 40 along their center line, the projections facing and engaging each other, and transversely arranged frames provided with seats for supporting the bar members and holding them in inclined position, the bar members 45 resting on their seats in this frame at their contacting lower edges.

2. In a grate, a grate bar for use with solid fuel, comprising two bar members arranged in an inclined position with their 50 lower edges in contact, longitudinal projections on the bar members approximately along their center line, the projections facing and engaging each other, transversely arranged frames provided with seats for 55 supporting the bar members and holding them in inclined position, and lifts interposed between the lower edges of said members and the bottoms of said seats.

In testimony whereof we, the said EMAN- 60 UELE RUFFO and VITO CALDERARO, have signed this specification at Rome, Italy, this 31st day of May, 1922.

EMANUELE RUFFO.
VITO CALDERARO.

In the presence of—
ANGELA CAROTTONI,
TARILLA FONHARY.
